COLANDER OR SIMILAR ARTICLE

Nathan W. Roop, Columbus, Ohio, assignor to Columbus Plastic Products, Inc., Columbus, Ohio, a corporation of Ohio

Application March 15, 1956, Serial No. 40,629

Term of patent 14 years

(Cl. D44—1)

FIG. 1.

FIG. 2.

FIG. 4.

FIG. 5.

FIG. 3.

FIG.6

Fig. 1 is a perspective view of a colander or similar article showing my new design;

Fig. 2 is a side elevational view;

Fig. 3 is a top plan view;

Fig. 4 is an enlarged fragmentary vertical sectional view taken along the line 4—4 of Fig. 3;

Fig. 5 is a similar view taken along the line 5—5 of Fig. 2; and

Fig. 6 is an enlarged fragmentary bottom plan view of a sector of the colander.

I claim:

The ornamental design for a colander or similar article, substantially as shown.
